US00D901671S

(12) **United States Design Patent** (10) **Patent No.:** **US D901,671 S**
(45) **Date of Patent:** **** Nov. 10, 2020**

(54) **INHALER**

(71) Applicant: **RPC Formatec GmbH**, Mellrichstadt (DE)

(72) Inventors: **Markus Thau**, Mellrichstadt (DE); **Axel Lenninghausen**, Wuppertal (DE)

(73) Assignee: **RPC Formatec GmbH**, Mellrichstadt (DE)

(**) Term: **15 Years**

(21) Appl. No.: **29/673,131**

(22) Filed: **Dec. 12, 2018**

(30) **Foreign Application Priority Data**

Nov. 28, 2018 (EM) 005837564

(51) **LOC (12) Cl.** **29-02**

(52) **U.S. Cl.**

(57) **CLAIM**

The ornamental design for an inhaler, as shown and described.

DESCRIPTION

FIG. 1 is a front, top and left side perspective view of an inhaler, showing our new design;

FIG. 2 is a front view thereof;

FIG. 3 is a left side view thereof;

FIG. 4 is a rear view thereof;

FIG. 5 is a right side view thereof;

FIG. 6 is a top view thereof;

FIG. 7 is a bottom view thereof;

FIG. 8 is a front, top and left side perspective view of an alternative embodiment of an inhaler, showing our new design;

FIG. 9 is a front view thereof;

FIG. 10 is a left side view thereof;

FIG. 11 is a rear view thereof;

FIG. 12 is a right side view thereof;

FIG. 13 is a top view thereof; and,

FIG. 14 is a bottom view thereof.

The features shown in broken lines depict portions of the inhaler that form no part of the claimed design.

1 Claim, 14 Drawing Sheets
